UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

BOWLING-ALLEY BALL RETURN.

Application filed January 9, 1924, Serial No. 685,112. Renewed September 14, 1925.

To all whom it may concern:

Be it known that I, JOSEPH W. BISHOP, a citizen of the United States, residing at Muskegon, in the county of Muskegon and State of Michigan, have invented certain new and useful Improvements in Bowling-Alley Ball Returns, of which the following is a specification.

This invention relates generally to bowling alleys and more particularly to the ball return.

In commercial practice it has been customary heretofore to provide a straight return for the ball extending from the alley pit to a curved end at or about the back of the approach to the alley whereby the ball is caused to travel upward to and forward on a receiving track elevated above the return track. As the ball travels up the curve 20 from the return track to the receiving track it is retarded so that it will come to rest upon the receiving track which provides storage space for a number of balls.

Many players desire to play exclusively 25 with a single ball, which may be owned by the player or may be a ball belonging to the alley, which the player prefers to the other balls, and therefore it is highly desirable to return this ball to the player as 30 quickly as possible, so that he may, whenever necessary, throw his second ball with as little delay as possible.

When the player delivers his first ball, he 35 usually remains at or about the foul line watching the ball travel down the alley to the pins, and it is desirable to return the ball direct to him while in this position without requiring him to look back for the ball to approach him from the rear of the 40 alley. The player's attention is primarily directed to the pins, and it may happen, while he is looking forward and at the same time picking up a ball from the track, another ball will travel up the curve to the 45 receiving track and hit the ball the player is picking up, or the line of balls, and injure the player's fingers. The finger holes in the balls are not always disposed in proper position for the player to engage 50 them, and quite frequently it becomes necessary to turn the ball around until the finger holes are accessible; if another ball travels up the curve and hits the player's ball, or the line of balls, while the player is turning

his ball, there is always the chance that the 55 player's fingers will be injured. It is my opinion that these chances of injury to the player will be eliminated and the operation of delivering the ball to the player simplified if the usual overhead return travel of the 60 ball is avoided, so that it will not be necessary for the player to direct his attention rearward in the act of picking up a ball. To this end my invention has for its object 65 to provide means for delivering the ball while in a forward direction from the return track, located at or about the level of the 70 alley bed, to the receiving or storage track elevated somewhat above the alley bed in convenient position for the players, and to retard the upward movement of the ball so that it will be delivered upon the receiving track at a rate of speed only sufficient for 75 such delivery.

I am aware that it has been proposed 75 heretofore to eliminate the return travel of the ball and permit it to travel in a straight line and up an incline to the receiving track, but the ball often travels down the return track at a comparatively high rate of speed 80 which must be checked and retarded to insure delivery upon the receiving track in a desirable manner without liability of injuring the player and without dislodging the 85 balls already on the receiving track; but so far as I know these devices have not proven commercially satisfactory because they lack efficient means for properly delivering the ball to the receiving track.

My invention, therefore, has for its object 90 also to provide a bowling alley ball return with means whereby the ball is delivered, while traveling forward, upon an elevated receiving track at a proper reduction in speed to insure safe delivery.

With these and other ends in view the invention comprises certain structural elements which are illustrated in what I now consider a preferred form in the accompanying drawings, wherein

Fig. 1 is a side elevation of so much of a bowling alley ball return as is necessary for illustrating my invention.

Fig. 2 is a transverse sectional view on the line 2—2 of Fig. 1.

Fig. 3 is a longitudinal sectional view on the line 3—3 of Fig. 2.

Referring to the drawings, 5 is a ball re-

turn of some approved construction which extends from the alley pit at the pin end of the alley and curves upward at 6 at the approach to the alley, and connects with the receiving track 7 which extends back to the post 8. At the juncture of the curved track 6 with the receiving track 7 there is a projecting point 9 where the ball changes completely its direction of travel. The ball 10 travels along the return track in a horizontal direction, then up the curve to a substantially perpendicular direction, and then it is caused to change again to a horizontal direction as it is carried over the point 9. This 15 last change of direction of travel of the ball is effected by guides 14 mounted in the frame 12 in an arc spaced from the point 9. The ball travels up the curve at a comparatively high rate of speed and it is checked and retarded by engagement with a tensioned buffer strap 10 while it is guided to change its direction of travel to a horizontal direction, and thus the ball is delivered very slowly and quietly on to the receiving track 7. The 20 frame 12 constitutes a support for the curved end 6 of the return track 5, for the guides 14 and for the buffer strap 10, and it may be located in any convenient position at the approach to the alley according to the 25 standard rules, or, if desired, according to any special requirements.

My invention provides a simple means for returning the ball to the player with a forward travel only and delivering it to the 30 player slowly so that the player may receive the ball as it is delivered upon the receiving track and without damage or injury. The delivery of a ball to the player while traveling in a forward direction from the 35 pit is desirable because it does not require a player to divert his attention from the pit end of the alley to which it is mostly directed, and also because it enables the player to receive the ball as it approaches him while 40 standing naturally adjacent the receiving track and without requiring him to twist around and strain to an unnatural position, or to turn his back to the pit end of the alley. The invention also insures delivery of 45 the ball at a rate of speed which can be regulated by tensioning the buffer strap and which is preferably reduced to a degree at which the ball will be delivered to the player slowly without endangering his fingers, or 50 will be aligned with other balls on the receiving track without crashing against them.

My invention is simple in construction and can be easily applied to old alleys as well as new alleys. I realize that changes in the details of construction may be required to

adapt the invention for different conditions, and I consider myself entitled to make all such changes as fairly fall within the scope of the following claims.

I claim:

1. A bowling alley ball return comprising a return track, an elevated receiving track in alignment with the return track, a curved track intermediate of the return track and the receiving track and connecting the adjacent ends thereof, and curved guide tracks disposed opposite to the juncture of the curved track with the receiving track. 65

2. A bowling alley ball return comprising a return track, an elevated receiving track in alignment with the return track, a curved track intermediate of the return track and the receiving track and connecting the adjacent ends thereof, means adjacent said curved track for changing the direction of travel of the ball when it reaches the top of the curved track and comprising guides, and a retarding buffer disposed opposite the juncture of the curved track with the receiving track. 70

3. A bowling alley ball return comprising a return track, an elevated receiving track in alignment with the return track, a curved track intermediate of the return track and the receiving track and connecting the adjacent ends thereof, a frame adjacent the curved track, and curved guides supported by the frame above the curved track. 75

4. A bowling alley ball return comprising a return track, an elevated receiving track in alignment with the return track, a curved track intermediate of the return track and the receiving track and connecting the adjacent ends thereof, a frame adjacent the curved track, guides supported by the frame above the curved track, and a retarding buffer carried by the frame and located opposite the juncture of the curved track with the receiving track. 80

5. A bowling alley ball return comprising a return track, an elevated receiving track in alignment with the return track, an upwardly curved track intermediate of the return track and the receiving track and connecting the adjacent ends thereof and forming a point at its juncture with the receiving track, guides above the curved track, and a resilient buffer arranged in an inclined position opposite said point to retard the travel of the ball at the point and cooperating with the guides for changing the direction of travel of the ball as it passes over the point. 85

JOSEPH W. BISHOP.
